UNITED STATES PATENT OFFICE.

RICHARD H. ARNTZEN, OF SERENA, ILLINOIS.

GUN.

Application filed November 1, 1921. Serial No. 512,021.

To all whom it may concern:

Be it known that I, RICHARD H. ARNTZEN, a citizen of the United States, residing at Serena, in the county of La Salle, State of Illinois, have invented a new and useful Gun; and I do hereby declare the following to be a full, clear, and exact description of the invention, such as will enable others skilled in the art to which it appertains to make and use the same.

The invention relates to guns of the multiple barrel type, and has for its object to provide a device of this character comprising a plurality of spaced gun barrels pivotally mounted in a block, and having slidably mounted on their muzzle ends a yoke which cooperates with angularly disposed members carried by the muzzle end of the gun and forms means whereby the muzzle ends of the guns may be adjusted outwardly or inwardly in relation to each other. The outward or inward adjustment of the muzzle ends of the guns allowing a plurality of shells to be bunched or spread as desired. A further object is to provide gear and shaft means whereby the yoke may be moved inwardly and outwardly, said yoke being slidably mounted on a centrally disposed gun barrel. With the above and other objects in view the invention resides in the combination and arrangement of parts as hereinafter set forth, shown in the drawings, described and claimed, it being understood that changes in the precise embodiment of the invention may be made within the scope of what is claimed without departing from the spirit of the invention.

In the drawings:—

Figure 1 is a longitudinal vertical sectional view through the gun.

Figure 2 is a vertical transverse sectional view through the gun taken on line 2—2 of Figure 1.

Figure 3 is a front view of the gun, showing the yoke block.

Referring to the drawings, the numeral 1 designates a stationary block which may be supported in any suitable manner by the arms 2 which rigidly hold the block 1 against movement. The block 1 is provided with a plurality of radially disposed elongated apertures 3, in which apertures are pivotally mounted the rear ends 4 of a plurality of gun barrels 5. The gun barrels 5 are so pivoted that they may pivot outwardly

radially on their pivotal points 3^a, the purpose of which will presently appear.

Rigidly secured in a centrally disposed aperture 6 in the block 1 is a gun barrel 7, which gun barrel is centrally disposed in relation to the other gun barrels 5, and does not move during the barrel adjusting operation hereinafter set forth.

Slidably mounted on the muzzle end 8 of the gun barrel 7 is a yoke 9, which yoke is provided with forwardly and outwardly extending rectangular shaped apertures 10, which receive the angularly disposed rectangular shaped portions 11 carried by the muzzle ends 12 of the gun barrels 5. It will be seen that when the yoke 9 is moved inwardly in the direction of the arrow *a* that the muzzle ends 12 of the gun barrels will be moved outwardly, thereby causing the shells or projectiles to be spread apart over a greater area, which is particularly advantageous in aircraft firing where the degree of accuracy on account of the moving of the airplane is uncertain. When the yoke 9 is moved outwardly in the direction of the arrow *b*, the muzzle ends 12 of the guns 5 will be moved inwardly thereby causing the shot or shell to be bunched. To accomplish the outward and inward movement of the yoke 9 a plurality of shafts 13 is provided, each rod 13 having its forward end provided with a threaded portion 14 which is threaded through the yoke 9. The rear ends of the shafts 13 are rotatably mounted in bearings 15 in the block 1 and are provided with pinions 16 which mesh with a gear 17 loosely mounted on the breech end 18 of the gun 7. Gear 17 is provided with a bevel gear 19 which bevel gear is rotated through the medium of an operating gear 20, carried by an operating shaft 21. It will be seen that when the operator grasps the operating handle 22 that the gear 17 will be rotated through the medium of the bevel gears 20 and 19 and that the shafts 13 will be simultaneously rotated through the medium of the pinion 16 thereby causing the yoke 9 to be adjusted inwardly or outwardly according to the direction of rotation of the shaft 21. The lugs 3^b, which form the pivotal points of the barrels 5 are preferably disposed in elongated slots 3^c, which slots allow sufficient radial movement of the barrels 5 to allow the outward radial movement of the barrels 5 in relation to the axis of the centrally disposed barrel 7.

2
Any kind of firing mechanism may be utilized, however for purposes of illustration a block 23 is disposed adjacent the breeches 24 of the gun barrels 5 and 7 and may 5 be provided with any suitable mechanism for cooperating with the firing pins 25 carried by the breeches 24.

From the above it will be seen that a 10 multiple gun is provided, which gun is simple in construction and so constructed that the operator may easily and quickly 15 adjust the gun barrels inwardly and outwardly in relation to each other, thereby allowing shot or shell from the various gun barrels to be spread or contracted as desired. It will also be seen that a gun is provided, which is particularly adapted for airplanes where extreme accuracy is practically impossible.

20 The invention having been set forth what is claimed as new and useful is:—

A gun comprising a block, a rigidly disposed gun barrel in said block, a plurality 25 of gun barrels radially movable in parallel relation to each other in radially disposed

slots in the block, a yoke through apertures of which the gun barrels extend, rectangular shaped angularly disposed integral blocks carried by the plurality of gun barrels and 30 slidably mounted in angular disposed bearings of the yoke, said rectangular shaped block extending rearwardly and inwardly towards each other, screws threaded in said yoke at points spaced from each other and 35 equidistant from each other, rearwardly extending shafts carried by said screws and rotatably mounted in bearings of the block, a gear rotatably mounted on the centrally disposed barrel, pinions carried by the rearwardly extending shafts and meshing with 40 said gear and means whereby said gear may be rotated for moving the yoke inwardly and outwardly as desired.

In testimony whereof I have signed my name to this specification in the presence of 45 two subscribing witnesses.

RICHARD H. ARNTZEN.
